(57) **CLAIM**

The ornamental design for a spherical ice cream maker, as shown and described.

DESCRIPTION

FIG. 1 is a perspective view of a spherical ice cream maker, in open position, showing my new design;

FIG. 2 is a perspective view thereof, in closed position;

FIG. 3 is a front elevation view thereof;

FIG. 4 is a back elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken line in the figure drawings represents unclaimed environment only and forms no part of the claimed design.
